GARMENT HANGER

Richard Battle, Los Angeles, Calif.

Application June 11, 1947, Serial No. 753,919

7 Claims. (Cl. 223—89)

1

My invention relates to improvements in garment hangers and more particularly to improvements in adjustable garment hangers and garment hangers which employ insect repellants.

The principal object of my invention is to provide an improved garment hanger of adjustable shape.

Another object of my invention is to provide a garment hanger which is adjustable both as to size and shape so that it may properly support garments such as coats of different sizes and shapes.

Another object of my invention is to provide a garment hanger which employs suspension means which rotatably engage two mutually pivoted hanger arms.

Another object of my invention is to provide a garment hanger with suspension means which includes perforated clamping means for closing opposite sides of a passage in which lumps of solid material, such as an insect repellant, may be enclosed.

Another object of my invention is to provide a shoulder piece which is adjustably attachable to the end of a hanger arm even while in use in supporting a garment.

Another object of my invention is to provide a shoulder piece to which a sachet may be readily attached.

The foregoing and other objects of my invention, together with various novel features thereof, will be understood more fully by reading the following detailed description in connection with the accompanying drawing. Although the invention is illustrated in the accompanying drawing and described hereinbelow with reference to a particular embodiment thereof, it is to be expressly understood that the drawing and description are illustrative only and that the invention is not limited to the specific details of the embodiment illustrated and described, the scope of the invention being defined by the appended claims.

In the drawings wherein like reference characters refer to like parts throughout the several views:

Figure 1 is a side elevational view of a garment hanger embodying features of my invention;

Fig. 2 is a vertical sectional view of the hanger taken on the line 2—2 of Fig. 1, illustrating the pivotal arrangement of the hanger arms;

Fig. 3 is a fragmentary view, partly in section, of one end of the hanger;

Fig. 4 is a vertical view taken on the line 4—4 of Fig. 1; and

2

Fig. 5 is a vertical sectional view of an alternative pivotal arrangement of the hanger arms.

Referring to the drawing, and particularly to Fig. 1, there is illustrated a garment hanger embodying the features of my invention and comprising two arms 10 pivotally held together with a suspension member 12 and provided with adjustable shoulder pieces 14 at their outer ends and interconnected by an adjusting mechanism 16 in the form of a turnbuckle. The arms 10 are preferably about 8½ inches in length and the turnbuckle of about 15 inches average length. The shoulder pieces 14 may be from about 2 to 4 inches in length.

To facilitate the pivotal arrangement of the two arms 10, the inner ends thereof are enlarged and respectively provided with mating circular tongue and groove portions 20 and 22 and two circular holes 24 concentric therewith. When the tongue and groove portions 20 and 22 are engaged, as illustrated in Fig. 2, the holes 24 register to form a passage 26 and the inner ends of the arms 10 are clamped together by means of a locking member 27 passing through the passage 26 and through two clamping plates 28 at the lower end of the hanger suspension member 12. Preferably the locking member 27 is in the form of a bolt terminating in a nut to provide easy access to the passage 26. Each plate 28 is provided with a plurality of perforations 30 in order that the passage may be ventilated to the atmosphere in order to obtain the maximum benefit from lumps 32 of solid material enclosed therein. It is to be understood, of course, that lumps of various types of solid material may be deposited in the passage 26 such as, for example, disinfectant, perfumes, deodorants, and moth balls, according to the user's purpose.

Preferably the suspension member 12 is made of two flat spring steel members 33 provided with hook-shaped portions 35 suitably secured together, such as by welding, to form a hook 36 and these hook portions terminate respectively in the clamping plates 28. The two plates 28 are symmetrically offset from the plane of the hook at the lower end thereof a distance about equal to the thickness of the tongue and groove portions 20 and 22 together. Also preferably the clamping plates 28 are dished inwardly in order to provide circular shoulders which can readily engage the faces of the hanger at opposite ends of the passage 26 in rotative sliding relationship with the hanger arms 10. These shoulders 40 operate with the tongue and groove 20 and 22 to

facilitate hinging the two arms 10 together at the pivot point.

The turnbuckle 16 which is used for angularly adjusting the arms about the pivot point, includes two oppositely threaded eye bolts 42 and an intervening rod 44 having threaded ends engaged therewith. The eye bolts 42 are pivotally supported by pins 46 within recess 48 in the lower side of the outer ends of the hanger arms 10, as illustrated in detail in Fig. 3. By means of the turnbuckle 16 the relative angular position of the two hanger arms 10 may be readily adjusted by turning the rod while the hanger is in use. The turnbuckle 16 not only acts to adjust the relative angular position of the hanger arms but also serves as a crossbar for supporting trousers and like garments.

Each of the shoulder pieces 14 comprises an upper portion and a lower portion which are arranged to envelop the outer end of a hanger arm 10. The upper portion is provided with laterally extending wings 56 which are curved downwardly and merge together at the outer ends thereof to present a downwardly curved surface upon which the shoulder of a coat or like garment can rest. A plurality of small holes 58 are arranged in the periphery of the upper portion of each shoulder piece 14 in order to permit ready attachment of a sachet 60 thereto by means of threads in the event that the hanger is to be used to support ladies' garments.

The lower portion of each shoulder piece 14 comprises a pair of inwardly opposed fingers 62 which are angularly shaped on the upper sides in order that they may fit readily in any one of a series of angular shaped slots 64 formed on the lower side of the outer ends of the hanger arms 10. Two opposed internal bosses 66 are formed in the lower portion in the longitudinal channel formed within each shoulder piece 14 to provide a pair of shoulders 68 which can engage the lower sides of tracks 70 extending laterally from the hanger arms 10 at the same time that fingers 62 engage slots 64 on opposite sides of the hanger arm. The slots 64 are preferably spaced about $\frac{1}{4}$ to $\frac{1}{2}$ inch apart along the length of the hanger arm 10.

In order to permit adjustment of each shoulder piece 14 on the hanger while in use and, at the same time, to provide for positive engagement of the fingers 62 with the slots 64 and the shoulders 68 with the rails 70, a strong leaf spring 72 is arranged in the channel 67 of the shoulder piece 14 and on the upper side of the hanger arm 10. This spring 72 is normally flexed outwardly and both ends 74 and 75 thereof normally engage the inner wall of the shoulder piece 14, one end 74 being rigidly secured thereto by any suitable means such as a rivet 76.

The spring 72 engages the hanger arm at a point which is offset from the line joining the point of contact of the fingers 62 and the shoulders 68 with the hanger arm 14 thus holding the shoulder piece 14 firmly against the hanger arm at these latter two points. By designing the spring 72 with sufficient strength, proper engagement of the shoulders 68 with the rails 70 and the fingers 62 with the slots 64 may be maintained while the hanger is in use supporting even heavy clothing such as an overcoat. And yet, by manual manipulation, the shoulder pieces 14 may be moved along the length of the respective hanger arms 10 and fixed in any desired position thereon by engaging the fingers 62 with suitable slots 64.

In an alternative pivotal arrangement of the two hanger arms, the tongue and groove portions illustrated in Fig. 2 are replaced by two flat abutting portions 80 as illustrated in Fig. 5. In the latter case the engagement of the clamping plates with the ends of the recess 26 is depended upon to hold the two arms 10 together firmly. In this form of the invention, two semi-circular slots 82 are arranged in the upper sides of the arms in order to form a vertical passage at the top side thereof through which lumps of a solid material may be deposited into the recess 26.

From the foregoing description of my invention it is clear that I have provided a garment hanger which is adjustable, both as to size and shape, so as to permit its being well-fitted to various garments. It is also clear that I have provided not only an improved adjustable hanger but that I have also provided improved shoulder pieces and improved hanger suspension means which are adapted for use with other hangers.

It is obvious that many modifications and variations may be made in my invention without departing from the true spirit thereof. It is, therefore, to be understood that my invention is not to be limited to the specific details shown and described but only by the appended claims.

I claim:

1. A garment hanger comprising a pair of pivotally arranged arms provided with a passage extending therethrough about the pivot axis, means for angularly adjusting said arms about the pivot axis, and suspension means including a hook member having a pair of perforated clamping plates attached thereto, said clamping plates being provided with shoulders rotatively engaging the portions of the walls of said arms at opposite ends of said passage, whereby a ventilated cavity is formed therein for enclosing solid material such as insect repellant.

2. A garment hanger comprising a supporting member provided with a passage extending therethrough, hanger suspension means including a hook member and a pair of perforated plate members resiliently secured to the lower end thereof, said plate members being relatively movable in opposite directions along an axis passing through said passage and means for securing said plate members on said supporting member on opposite sides of said passage in closing relationship therewith, whereby solid material such as an insect repellant may be enclosed therein.

3. A garment hanger comprising a supporting member provided with a passage extending therethrough, hanger suspension means including a hook member and a pair of perforated plate members resiliently secured to the lower end thereof, and a bolt passing through said plate members and said passage for securing said plate members on said supporting member in closing relationship with opposite sides of said passage, whereby solid material such as an insect repellant may be enclosed therein.

4. A garment hanger comprising a supporting member provided with a circular passage extending therethrough, hanger suspension means including a hook member and a pair of perforated plate members resiliently secured to the lower end thereof, said plate members being provided with circular shoulder portions rotatively engaging opposite faces of said hanger at the opposite ends of said passage, and means including a pin member passing through said plate members and said passage for securing said plate members on said supporting member in closing relationship

with opposite sides of said passage, whereby solid material such as an insect repellent may be enclosed therein.

5. A garment hanger comprising two arms respectively provided with mating circular tongue and groove portions, said portions being provided with registered holes forming a passage concentric with said tongue and groove portions, suspension means including a hook and a pair of plate members attached thereto, said plate members being held in closing relationship with opposite ends of said passage and in rotatively sliding relationship with said arms to form a cavity therein, and means for angularly adjusting said arms about a pivot point concentric with said tongue and groove portions.

6. A garment hanger as defined in claim 5 wherein said plate members are perforated to provide ventilation between said passage and the surrounding atmosphere.

7. A garment hanger comprising a pair of arms, two ends of the respective arms being slidably engaged for angular movement about a pivot axis, said ends being formed to provide a passage extending through said ends, said pivot axis extending through said passage, suspension means including a pair of perforated clamping members

rotatively engaging opposite faces of said hanger at the opposite ends of said passage, said clamping members rotatively supporting said arms for mutual angular movement about said pivot axis, a suspension hook attached to said clamping members, and means interconnecting said arms for angularly adjusting said arms about the pivot axis.
